LENS

Kurt Franck, Newark, Ohio, assignor to Holophane Company, Inc., New York, N.Y., a corporation of Delaware

Filed Nov. 18, 1959, Ser. No. 58,385

Term of patent 14 years

(Cl. D48—16)

Fig. 1 is a bottom perspective view of a lens showing my new design;

Fig. 2 is a section taken along the lines 2—2 of Fig. 1;

Fig. 3 is a section taken along the lines 3—3 of Fig. 1; and

Fig. 4 is an enlarged fragmentary perspective taken in the area 4 of Fig. 1.

I claim:

The ornamental design for a lens, as shown.
